(57) **CLAIM**

We claim the ornamental design for an electric oven range, as shown and described.

DESCRIPTION

FIG. 1 is a top, front and right-side perspective view of an electric oven range showing our new design;

FIG. 2 is a bottom, front and right-side perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a top, front and right-side perspective view of the electric oven range showing an alternative configuration with the slide-out hood;

FIG. 10 is a bottom, front and right-side perspective view thereof;

FIG. 11 is a front elevation view thereof;

FIG. 12 is a rear elevation view thereof;

FIG. 13 is a left-side elevation view thereof;

FIG. 14 is a right-side elevation view thereof;

FIG. 15 is a top plan view thereof;

FIG. 16 is a bottom plan view thereof;

FIG. 17 is another front elevation view of the electric oven range shown in an environment of use with a touch screen on the lower portion; and,

FIG. 18 is a front elevation view of the electric oven range shown in another environment of use.

The evenly-spaced broken lines shown in FIGS. 1-18 depict portions of the electric oven range or environmental structure.

(Continued)

ture that form no part of the claimed design. The icons and numbers shown on the touchscreen in FIG. 17 illustrate environment and form no part of the claimed design. The dot-dot-dash broken line showing the border and the remaining broken line except for the subject article in FIG. 18 illustrate environment and form no part of the claimed design.
